UNITED STATES PATENT OFFICE.

THADDEUS F. BAILY, OF ALLIANCE, OHIO, ASSIGNOR TO THE ELECTRIC FURNACE COMPANY, OF ALLIANCE, OHIO, A CORPORATION OF OHIO.

ANNEALING-FURNACE.

1,238,908.

Specification of Letters Patent. Patented Dec. 10, 1918.

Application filed January 31, 1918. Serial No. 214,570.

To all whom it may concern:

Be it known that I, THADDEUS F. BAILY, a citizen of the United States, residing at Alliance, in the county of Stark and State of Ohio, have invented a new and useful Annealing-Furnace, of which the following is a specification.

This invention relates to annealing furnaces and has more especial reference to continuous furnaces for annealing heat treating and the like.

The object of this invention is to transfer heat from the out-going finished product to the in-coming raw material.

Another object is the provision of an annealing furnace comprising a heating chamber and elongated regenerative hood and two trains of material moving in opposite directions through the hood and heating chamber.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims without departing from the spirit or sacrificing any of the advantages of the invention.

In the drawings:

Figure 1 is a plan view of the furnace. Fig. 2 is a side elevation partly in section of the same.

Fig. 3 is a section on an enlarged scale on the line 3—3, Fig. 1.

Fig. 4 is a section on the line 4—4, Fig. 3. Similar numerals of reference indicate corresponding parts throughout the several figures of the drawings.

Referring more especially to the construction illustrated in the accompanying drawings, the numeral 1 indicates the heating furnace which may be heated by any suitable means although in the drawings electric heating devices are shown. Resistance troughs 2 are provided in the heating chamber, said resistance troughs being composed of a refractory material such as fire clay or the like and contains a granular resistance material indicated by the numeral 3. Carbon electrodes 4 of the usual construction, are located within the granular resistance

material in the usual manner for the purpose of completing an electric circuit through the resistance material.

A hood 5 of any desired length communicates with said heating furnace, said hood 5 being open at its other extremity to the outer air. A hood 6, similar to the hood 5 is provided at the other end of the furnace, said hood open at its outer end. The heating furnace is thus located at substantially the center of the device, the hoods 5 and 6 being of substantially equal length, each of these hoods extending a sufficient distance from the heating furnace 1 to accomplish the desired results. The material is passed through the furnace in two oppositely moving trains, each of which is passed through one of the hoods through the heating furnace and then through the other hood, each in-coming unit of raw material absorbing the heat from the adjacent out-going units of finished material and then passing through the heating chamber after which it in the same manner carries off its heat to the in-coming raw material as it passes through the other hood.

It will thus be seen that the hoods 5 and 6 produce a regenerative operation, the heat given off by the out-going material instead of being wasted in the outer air is absorbed by the in-going material while passing through the said hoods. The hoods may therefore be specifically called regenerative hoods.

For the sake of illustration the trains are shown in the drawings as made up of cars traveling upon the tracks 8 and 9 respectively in the direction of the arrows shown thereon. Each car 10 is shown as a flat car provided with spaced transversely disposed passages 11 to allow a circulation of air therethrough and the packs 12 of material are carried upon said cars as shown. Any suitable device may be provided for pushing the trains of material through the furnace such for instance as the screws 13 which are operated through the gearing 14 by means of a motor 15. It will, of course, be understood that this specific form of pusher device has no connection with the invention other than that some means of pushing the trains of material through the furnace if necessary. The cars loaded with material are moved from the storage tracks 16 at each end of the device, to the trucks 110.

17, which trucks are designed to be moved laterally upon the tracks 18 until the cars are brought into alinement with the in-going tracks, as shown in Fig. 1, after which the 5 adjacent pusher is operated sufficiently to move said car inside of the regenerative hood where it absorbs some of the heat from the adjacent out-going car from the other track. As this operation is repeated each 10 particular car is successively moved step by step through the first regenerative hood while the other train is being moved in the opposite direction, thus taking some of the heat from each car or unit of material in 15 passing the same after which each car passes through the heating furnace and then in the same manner is passed step by step through the other regenerative hood giving up some of its heat to each adjacent in-coming car 20 or unit of material in the opposite train. By this process the in-going raw material conserves the heat from the out-going finished material, that would otherwise be lost were the train of finished material 25 run directly into the outside atmosphere and no regenerative hood used, thus the amount of heat necessary for the resistors within the heating furnace to supply, is greatly reduced, a large percentage of the heat carried 30 out of the heating chamber by the finished material being absorbed and returned by the raw material.

I claim:

1. An annealing furnace consisting of a 35 heating furnace and a regenerative hood, said heating furnace located at the center of said regenerative hood and arranged to receive heat generated by resistance to electric current in suitable resistance elements 40 placed longitudinally in the sides of said heating furnace and two parallel trains of material arranged to move in opposite di-

rections through said regenerative hood and heating furnace.

2. An annealing furnace consisting of a 45 heating furnace and a regenerative hood, one end of said regenerative hood communicating with said heating furnace and the other end thereof open to the atmosphere, and two parallel trains of material arranged 50 to move in opposite directions through said regenerative hood and heating furnace.

3. An annealing furnace consisting of a heating furnace and a regenerative hood, the walls of said furnace and hood consisting of heat resistance materials and two parallel trains of material moving in opposite directions through said regenerative hood and heating furnace. 55

4. An annealing furnace consisting of a 60 heating furnace and a regenerative hood, and two trains of cars moving in opposite parallel directions through said annealing furnace, the ends and floors of said cars being constructed of refractory and heat insulating material. 65

5. An annealing furnace consisting of a heating furnace and a regenerative hood and two trains of cars moving in opposite parallel directions through said annealing 70 furnace and means for preventing loss of heat between the floors of said cars and the walls of said furnace and hood.

6. A furnace of the character described comprising an enlarged heating chamber, 75 an elongated regenerative hood communicating with each end of said heating chamber and two trains of material moving in opposite parallel directions through said regenerative hoods and heating chamber. 80

In testimony that I claim the above I have hereunto subscribed my name.

THADDEUS F. BAILY.
